PIPE HANGER

Filed April 8, 1930

Inventor

P. J. Neilon

By Watson E. Coleman
Attorney

UNITED STATES PATENT OFFICE

PATRICK J. NEILON, OF EAST CLEVELAND, OHIO

PIPE HANGER

Application filed April 8, 1930. Serial No. 442,604.

This invention relates to pipe hangers and particularly to pipe hangers formed of two hinged sections, the invention particularly relating to the means whereby the sections are disposed in conjunction with each other at their free ends and operatively connected to a supporting bolt or eye.

The general object of the invention is to provide a very simple pipe support which may be cheaply made, easily put in place and has been found very effective in practice.

My invention is illustrated in the accompanying drawings, wherein:—

Figure 1 is an elevation of a pipe hanger constructed in accordance with my invention, the pipe being shown in section;

Figure 2 is a fragmentary elevation showing the upper end of the hanger illustrated in Figure 1, but with a different connection to the support.

Referring to the drawings, it will be seen that my improved pipe hanger consists of two arcuate sections 10 and 11 hinged at 12 adapted to embrace the pipe 13. The free ends of the sections are bent outward at an angle as at 14 in outwardly convergent relation and then extended straight outward, that is, radially outward as at 15 and then again angularly bent as at 16, the angularly bent portion being disposed beneath or in overlapping relation to the angularly bent portion of the other section.

These two portions are provided with apertures for the passage of the bolt 17 provided with the nuts 18. The portion 15 and the two sections are apertured as at 19 whereby an eye rod 20 may be engaged with the hanger by means of a bolt 21.

It will be understood that the supporting member 16 in Figure 1 or 21 in Figure 2 may be either a machine threaded bolt, a lag screw or an eye rod as desired. The hinge 12 may be formed by providing eyes on the adjacent extremities of the two sections and connecting these eyes by a bolt and nut passing through the eyes or by a rivet.

I claim:

1. A pipe hanger of the character described, comprising two sections hinged to each other, the sections at their free ends

being bent upward and inward in convergent relation to each other, then extending upward and then horizontally whereby said angular extremities may be disposed in overlapping relation, the angular extremities being apertured for the passage of a supporting member.

2. A pipe hanger of the character described, comprising two sections hinged to each other, the sections at their free ends being bent upward and inward in convergent relation to each other, then extending upward and then horizontally whereby said angular extremities may be disposed in overlapping relation, the horizontally disposed angular extremities and the vertically disposed portions immediately beneath them being apertured for engagement with a supporting member.

In testimony whereof I hereunto affix my signature.

PATRICK J. NEILON.
